UNITED STATES PATENT OFFICE.

FRED MATHEWS, OF CHICAGO, ILLINOIS, ASSIGNOR, BY MESNE ASSIGNMENTS, TO
WALTER P. MURPHY, OF NEW YORK, N. Y.

CAR-DOOR FASTENER.

1,322,499.

Specification of Letters Patent. Patented Nov. 18, 1919.

Application filed May 3, 1917. Serial No. 166,083.

To all whom it may concern:

Be it known that I, FRED MATHEWS, a citizen of the United States, residing at Chicago, in the county of Cook and State of Illinois, have invented new and useful Improvements in Car-Door Fasteners, of which the following is a full, clear, and exact description.

My invention relates to sliding door fasteners, and particularly to fasteners for the rear edge of sliding car doors when closed.

The object of my invention is not only to fasten the sliding door when closed, but also to move the door tightly against the door-post, by means which withdraw from the recess in the door-post into the door when unlocked and does not interfere with the movement of the door when it is desired to open the same, substantially as hereinafter fully described, and as particularly pointed out in the claims.

In the drawings:

Figure 1 is a front view of my invention showing it applied to a fragment of a sliding car door and side of a car.

Fig. 2 is a horizontal section of the same taken on dotted line 2—2, Fig. 1.

Fig. 3 is a vertical transverse section taken on dotted line 3—3, Fig. 1.

Fig. 4 is an edge view of the door showing said lock fixtures in side elevation.

Fig. 5 is a vertical transverse section taken on dotted line 5—5, Fig. 3.

Fig. 6 is a front view of a fragment of the plate in which the bolt hole is made and a transverse section of the inner reduced end of said bolt therein, said figure being on the line 6—6 of Fig. 3.

Fig. 7 is a perspective view of the bolt segregated from the remainder of the fastener.

Referring to the drawings, A represents a fragment of the side wall of a car body; B the rear post of the door-frame thereof and C the broken away portion of a sliding car door to which my improvements are applied. At a suitable point in the outer surface of the door post a recess *a* is made, and the mouth of this recess is closed by a flat plate *b* which has a hole *c* therein through which the bolt is adapted to be shot or withdrawn, as will hereinafter be more fully explained.

This bolt 7 has a cylindrical body which is rotatively seated in the bore of a tubular cas-

ing 8, which latter projects transversely 55 through the door structure from a metal plate 9 that is secured by rivets or bolts to the outer surface of the door next its rear edge. The body of the bolt extends from end to end of the bore of the casing 8 and its 60 outer end is reduced and extends beyond plate 9 and has the boss 10 of a handle 12 securely mounted thereon.

When the bolt is shot into recess *a* so as to lock the door the handle thereof will extend 65 to the left in a horizontal position, and when said bolt is rotated into such position as to be withdrawn from recess *a* and unlock the door, the handle will be in a horizontal position and extend to the right. When the handle 70 is at the limit of its left hand motion it will rest upon a bracket 13 projecting outward from plate 9, and which has an opening 14 therein that alines with an opening 15 in the shaft of said handle. If desired, the 75 yoke of a seal 16 may be passed through these openings 14 and 15 and its ends properly fastened in the usual manner when the door is locked. When the door is unlocked, handle 12 will rest upon a bracket 17 projecting from plate 9 on the side of casing 8 80 opposite bracket 13.

The cylindrical body of the bolt has a pin 18 projecting laterally therefrom near its inner end, and this pin is adapted to enter 85 and engage a spiral groove 19 made in the inner circumference of the bore of casing 8, which latter extends from a point near the inner end of said bore to the outer end thereof. The inner end of the groove terminates in a transverse segmental portion 19^a. 90

When the bolt is at the limit of its outward movement pin 18 will engage the outer end portion of the spiral groove 19 and when it is rotated to the left the engagement of 95 the pin with the groove forces the bolt inward until the pin arrives at the inner end of the spiral portion of the groove, whereupon the longitudinal movement of the bolt ceases and it moves on its axis to the extent 100 permitted by the transverse segmental portion 19^a of the groove. When the bolt arrives at the limit of its inward movement the inner reduced end of the bolt will have passed through bolt-hole *c* in plate *b* and the head 105 21 projecting transversely from its inner end will be within the confines of recess *a*. When the bolt has arrived at this last mentioned

position, pin 18 will enter the transverse segmental portion of the groove, and as said bolt is rotated to the extent of said segmental portion, head 21 will engage the inner 5 inclined surface of a segmental rib 22 situated on the inside of plate 6, the curvature of which is struck from the pivotal center of said head, and thus draws the door tightly against the door-post, or substantially so.

10 When the bolt is turned from left to right, at the start of its movement, the bolt rotates on its axis until head 21 thereof is in position to be withdrawn from bolt-hole *c* whereupon the engagement of pin 18 with 15 the spiral part of the groove moves the bolt outward and withdraws the head out of recess *a*.

What I claim as new is:

1. The combination with a sliding door, 20 the door-post of a door-frame, and a plate covering over a recess in the outer surface of said post that has a bolt opening therein, of a tubular bearing carried by said door and a bolt journaled in said bearing, one of said 25 last named two elements having a spiral groove which terminates in a transverse segmental portion and the other having a pin projecting therefrom that enters and engages the groove, said bolt being provided 30 with a laterally projecting head on its inner extremity, and means for rotating said bolt and causing the head thereof to move into or out of said recess, said pin being positioned to enter the transverse segmental por-

tion of the groove when the head enters the 35 recess.

2. The combination with a door jamb, and a door to be drawn against the same, of a plate spanning a recess formed in the jamb, 40 said plate being apertured for passage of a bolt, a cam formed on the plate on its side toward said recess, a bolt bearing mounted in the door in register with the plate aperture, a locking bolt mounted in the bearing, one of said last mentioned two elements 45 formed with a spiral groove terminating at the inner end in an arcuate groove concentric with the axis of the bearing, a guiding pin fixed in the other of said elements and traveling in said groove, and a cam lug 50 formed on the inner end of the bolt and movable into engagement with said cam by inward travel of the pin in the spiral portion of the groove, the arcuate portion of the groove being of sufficient length to accommodate the movement of the pin incident to travel of said lug upon the cam, and said pin being so positioned as to leave the spiral portion of the groove and enter the arcuate portion thereof to permit the lug to be moved 55 against the cam.

In witness whereof I have hereunto set my hand this 31st day of March, 1917.

FRED MATHEWS.
